UNITED STATES PATENT OFFICE.

CHARLES K. PICKLES AND JOHN A. HOFF, OF ST. LOUIS, MISSOURI, ASSIGNEES, BY MESNE ASSIGNMENTS, TO THE AMERICAN STENCIL MACHINE COMPANY, OF EAST ST. LOUIS, ILLINOIS.

STENCIL-CUTTING MACHINE.

SPECIFICATION forming part of Letters Patent No. 544,193, dated August 6, 1895.

Application filed October 18, 1894. Serial No. 526,308. (No model.)

To all whom it may concern:

Be it known that we, CHARLES K. PICKLES and JOHN A. HOFF, citizens of the United States, and residents of St. Louis, in the State of Missouri, have invented new and useful Improvements in Stencil-Cutting Machines, of which the following is a specification.

The object of our invention is to provide improved means for cutting stencil-letters in sheets of paper, card-board, and analogous substances, and to feed the said card-board or stencil-sheet across the plane of the cutting mechanism in advance of the cutting operation.

15 Our invention comprises a table, a matrix-plate mounted for horizontal rotation on said table, a patrinx-plate mounted for horizontal rotation on said table and locked to said matrix-plate, an index-ring, a yoke mounted for horizontal rotation independently of or conjunctively with the patrinx and matrix plates, a hand-lever mounted for oscillation in said yoke and adapted for manual actuation, feeding mechanism adapted to be acted upon by 25 said lever, and means whereby said lever may be caused to successively and progressively independently actuate the patrices.

Our invention further comprises the construction, arrangement, and combination of 30 parts hereinafter set forth, pointed out in our claims, and illustrated by the accompanying drawings, in which—

Figure 1 is a plan view showing the device in position for actual use. Fig. 2 is a detailed plan of a portion of the matrix-plate. Fig. 3 is a sectional elevation on the indicated line 3 3 of Fig. 1. Fig. 4 is a front elevation of the feeding mechanism. Fig. 5 is a sectional elevation of the feeding mechanism. 35 Fig. 6 is a detailed elevation in section of the cutting and feeding mechanisms in one position. Fig. 7 is a detailed elevation in section of the cutting and feeding mechanisms in another position. Fig. 8 is a detailed sectional plan on the line 8 8 of Fig. 3. Fig. 9 is an elevation of the patrinx-operating bolt.

In the construction of the machine as shown the numeral 10 designates a table having a central concavo-convex portion 11, centrally 40 apertured and provided with a bossed hub 12,

within which is vertically positioned a bolt 13, having a shoulder 14 nearest its lower end portion, adapted to impinge against the upper surface of said hub, and held in its seat by means of nuts 15, mounted on the screw-threaded lower end portion of said bolt.

55 Mounted for rotation horizontally on the bolt 13 and resting on the shoulder 14 of said bolt 13 is a matrix-plate 16, having a central vertically-apertured hub 17, forming the bearing on said bolt, and transverse radial ribs 18, cast integral with said plate and hub. A rim 19 is formed on and extends downwardly from the periphery of the matrix-plate 16, which rim is vertically apertured in series and recessed in its upper face, a plurality of matrices 20 being mounted in the recess of said rim and secured to the plate by means of screws 21, as shown in detail in Fig. 2.

60 Mounted upon the bolt 13, above the matrix-plate 16, is a patrinx-plate 22, which patrinx-plate has a central vertically-apertured hub 23 resting on the hub 17, and secured thereto and adapted for horizontal rotation on the said bolt conjunctively with the matrix-plate. The patrinx-plate is provided with a plurality of radial strengthening ribs 24 and a peripheral upwardly-extending integral rim 25, in which rim a series of hubs is formed, each of which hubs is vertically apertured 65 and has mounted therein a patrinx 26, which patrinx is adapted for vertical reciprocation in its seat, the series of patrices vertically aligning with the series of matrices 20. Each patrinx 26 is provided with a head 27 on its lower end, which head carries a symbolical configuration coincident with the aperture representing a symbolical configuration in the matrix 20 beneath the same, and a retractile spring 28, one end of which spring is passed through a perforation transversely located in the upper portion of the patrinx, the opposite end of said spring being seated in a guide-rim 29 on the patrinx-plate. Recesses 30 70 are formed in the inner and outer faces, respectively, of the patrinx 26 near the upper end of said patrinx, for a purpose hereinafter to be explained.

75 The guide-rim 29 is located on and fixed to the radial ribs 24 of the patrinx-plate, and is 80 85 90 95 100

- provided with a series of upwardly-extending inclined posts or studs 31 corresponding in number with the patrices 26 and providing spaces in radial alignment with said patrices.
- 5 The perimetral edges of the posts 31 are attenuated, thus providing flaring sides for the spaces between said posts.
- An index-ring is formed integral with the guide-rim 29, which index-ring is designated 10 as 32 and bears upon its upper surface symbols corresponding with the symbolical configurations of the patrices and matrices.
- The index-ring, guide-rim, patrices, and matrices are concentric with the bolt 13 and 15 have a common vertical axis, which is the axis of said bolt. A collar 33 is mounted loosely on the bolt 13 in contact with the upper surface of the hub 23, and a yoke-bar 34, having a central vertically-apertured hub 35, 20 is mounted on the bolt 13 in contact with the upper surface of the collar 33, and is adapted for horizontal rotation on said bolt, being held to its seat by means of a washer 36 and nuts 37. The yoke-bar is formed with a 25 downwardly-turned bossed end portion 38, having a flattened surface, which portion 38 rests upon and has a sliding bearing with a ring 39 formed on or fixed to the table 10 concentric with the depressed portion 11 of said 30 table and vertically extending therefrom. The end portion of the yoke-bar 34 opposite to the portion 38 is bifurcated, and a hand-lever 40 is mounted for oscillation on a pin 41, transversely seated in said bifurcation, the 35 lower portion of said hand-lever extending through said bifurcation and being provided with a tongue 42, adapted for engagement with the guide-posts 31. The yoke-bar 34 is provided with a vertically-apertured bossed portion 43, in which is mounted for vertical reciprocation a patrix-operating bolt 44, Fig. 9, which bolt has downwardly-extending converging arms 45 45, adapted for engagement in the recesses 30 30 of the patrices 26. The 45 bolt 44 is transversely slotted at 46, and a bolt-lever 47, mounted on the pin 41 within a bifurcation 48 in the hand-lever 40 and having an arm 49, passes through said slot and has a limited vertical movement therein. The bolt-lever 47 has a notched arm 50, the notch in said arm being adapted to embrace a pin 51, transversely seated in the bifurcation of the lever 40, the dimension of said notch being materially greater than the diameter of said pin 51. A retractile spring 52, fixed at one end to the hand-lever 40 and at the other end to a stud 53, mounted on the yoke-bar 34, serves to retain the said lever in a vertical position.
- The arm 49 of the bolt-lever 47 extends 60 through and beyond the slot 46 in the bolt 44, and is pivotally connected at its extremity with the upper end of a bolt 57, mounted for vertical reciprocation in the extreme outer end of the yoke-bar 34. The lower end of the bolt 57 is conoidal and normally occupies a position in an aperture 58 in the ring 39, adjacent to the front of the machine, which ap-

erture 58 connects with a slot 59, also formed in said ring. A trigger 60 is pivotally mounted at its lower ends on a pin 61, transversely seated in the ring 39 below the slot 59, which trigger is provided with an apiced upper end 62, having an inclined forward face 63 normally in the vertical plane of the bolt 57. A retractile spring 64, fixed at one end to the ring 39 and at the other end to the upper end portion of the trigger 60, serves to retain said trigger in a normal position, the trigger being retained against lateral movement by engagement in the slot 59. A clip 65 is pivotally mounted at one end on a pin 66, seated horizontally in the ring 39, which clip is provided with an aperture 67 in the end thereof opposite to the pin 66, in which aperture is mounted an eccentric 68, 85 pivoted on a pin 69 mounted in the ring 39, which eccentric has a handle 70 adapted for manual actuation to rotate the same. A pivotal pin 71 is transversely positioned in the central portion of the clip 65, and a feed-wheel 72 is pivotally mounted on said pin, which feed-wheel has integrally formed thereon a ratchet-wheel 73, Fig. 5. A gravity-pawl 74, having a hooked forward end 75, is fulcrumed on the upper end portion of the trigger 60 and engages with the teeth of the ratchet-wheel 73. An aperture 76 is formed in the table 10 in alignment with the feed-wheel 72, through which aperture projects a follower feed-wheel 77, having the apex of its periphery flush with the upper surface of the table 10, the said wheel 77 being rotatably mounted in the forward end of a retractile leaf-spring 78, secured to and below the table 10. An expansive leaf-spring 79 is fixed at one end to the horizontal portion of the ring 39 and impinges at its other end against a laterally-extending lug 80 on the movable end portion of the clip 65, the tendency of said spring being to depress the said clip and hold the same in rigid engagement with the eccentric 68. A depressing spring-arm 81 is fixed at one end to the clip 65 above the eccentric 68, and extending rearwardly from said clip in the longitudinal plane thereof has pivotally mounted in its outer end a serrated guide-wheel 82, the resilience of said arm being adjusted by means of an adjusting-screw 83, mounted in said arm and impinging against the said clip. This arm and the wheel provide a trailer for supporting the rear end of the clip.

A series of perforations 84 are formed in the table 10 in a radial line longitudinally of said table from the axis of the bolt 13, which perforations are adapted to receive at different times a pin 85, by means of which pin a stencil-sheet 86 is provided with an axis of rotation and held in a fixed relation to the said table.

An index-finger 87 is fixed to and extends laterally from the hub 35 of the yoke-bar 34, the extremity of said finger being in vertical alignment with the index-ring 32.

The practical use of this machine involves

an operation as follows: The stencil-sheet 86 is introduced beneath the feed mechanism and in alignment with and between the patrinx and matrix plates by manual operation, the 5 clip 65 being first oscillated by the rotation of the eccentric 68 to elevate the feed-wheel 72 out of engagement with the follower 77, the said clip being repositioned, as shown in Fig. 4, after the insertion of the stencil-sheet. 10 If it be desired to cut a series of apertures in the stencil-sheet concentric with the center of said sheet, the pin 85 is positioned as shown in Fig. 1, the sheet being held in engagement with the table at its peripheral portion by the 15 guide-wheel 82 through the tension of the arm 81. The hand-lever 40 being in the position shown in Figs. 3 and 1, it is moved in an orbit concentric with the bolt 30 by manual operation until such time as the index-finger 20 87 indicates the symbol to be first employed on the stencil-sheet, at which time said hand-lever is oscillated into the position shown by dotted lines in Fig. 3, thus bringing the tongue 42 of said lever into a space between two of 25 the guide-posts 31, as designated in Fig. 6. A continuation of the orbital movement of the hand-lever 40 causes a rotation of the yoke-bar 34, patrinx-plate 22, and matrix-plate 16 conjunctively, and such orbital movement is continued until the bolt 57 is brought into vertical 30 alignment with the aperture 58 of the ring 39. At this time the hand-lever 40 is moved outwardly from the vertical, thus causing an engagement of the pin 51 with the outer arm of 35 the bifurcated end portion 50 of the lever 47, thus oscillating said bolt-lever 47 on its fulcrum 41 and causing a depression of the outer end of the arm 49, which by reason of its pivotal connection with the bolt 57 depresses said 40 bolt into engagement with the inclined face 63 of the trigger 60, this movement of depression being permitted independently of any movement of the bolt 44 by reason of the slot 46 in said bolt having a greater length than the 45 vertical dimension of said arm 49. A continuation of the depressing movement of the bolt 57 after the engagement of said bolt with the inclined face 63 of the trigger 60 oscillates said trigger on its fulcrum 61, and by 50 reason of the rigid connection of the pawl 74 and said trigger the said pawl is caused to engage with the ratchet-wheel 73 and rotate said ratchet-wheel, the movement of rotation of said ratchet-wheel being synchronously imparted to the feed-wheel 72, and the stencil-sheet being retained between said feed-wheel and the follower 77 it follows that upon the 55 rotation of said feed-wheel the stencil-sheet will be advanced, the line of advance being determined by the engagement of the guide-wheel 82 and its relation to the pin 85. The further oscillation outwardly of the hand-lever 40 brings the arm 49 of the lever 47 to the limit of the slot 46 in the bolt 44 and 60 causes an engagement of said arm with said bolt, which depresses the said bolt in contact with the patrinx 26 in alignment therewith and

forces said patrinx downwardly through the paper or stencil sheet and meshes the symbolical configuration of the patrinx with the 70 aperture of the matrix, thus forming a puncture of the stencil-sheet. Upon the completion of the downward movement of the patrinx the hand-lever 40 is released from manual pressure and is reseated automatically 75 through the resilience of the spring 52 in a vertical position, the engagement of the pin 51 with the inner arm of the lever 47 oscillating said lever 47 and causing the arm 49 thereof to elevate the bolts 44 57, and by reason of the engagement of the hooks 45 in the recesses 30 of the patrinx also elevating said patrinx, the said elevation of said patrinx being assisted by the resilience of the spring 28.

A succession of the above-described movements will result in the successive and progressive formation of letters and symbols in the stencil-sheet.

When it is desired to form parallel transverse lines of perforations in the stencil-sheet, 90 the pin 85 is removed and the said sheet permitted to cross the table 10 under the influence of the feed mechanism and the guide-wheel.

What we claim is—

1. A stencil cutting machine comprising a table, matrix and patrinx plates mounted for conjunctive rotation on said table and separated a short distance from each other, a yoke-bar mounted for rotation independently of 100 or conjunctively with said plates, patrices mounted in said patrinx plate and adapted for vertical reciprocation therein, an operating bolt mounted in said yoke bar, a hand-lever fulcrumed in said yoke bar and adapted for 105 manual actuation, a bolt-lever fulcrumed in said hand-lever, connections between said levers, and feed mechanism and means whereby the feed mechanism is connected with said bolt-lever as set forth. 110

2. In a machine of the class described a yoke-bar having a bifurcated end portion, a hand-lever mounted for manual oscillation in the bifurcation of said yoke-bar and having a bifurcated portion, a bolt-lever mounted in 115 the bifurcated portion of the hand-lever and having a common fulcrum therewith and a notched end portion, a pin in said hand-lever having a travel in said notch and engagement with the bolt-lever, patrinx and matrix plates, 120 patrices, an operating bolt, and a table.

3. In a machine of the class described a table having a vertically extending ring, an axial bolt, patrinx plate having guide-posts and matrix plate mounted on said axial bolt within 125 said ring, a yoke bar mounted on said axial bolt and in engagement with said ring at both ends, which yoke bar is provided with a bifurcated portion, a hand-lever mounted in said bifurcated portion of said yoke bar the patrinx 130 operating bolt, means for operating the latter from the hand-lever and a tongue on said hand-lever forming a connection between said yoke bar and the guide posts of the patrinx plate.

4. In a machine of the class described a patrrix plate having a series of patrices therein, a yoke bar located above said patrrix plate, an operating bolt mounted for vertical reciprocation in said yoke bar and mechanism whereby said operating bolt is caused to engage individual patrices consisting of a hand-lever, a bolt-lever engaging the bolt, a pivot pin common to both of the levers whereby the latter are pivoted to the yoke-bar, and pin and slot connection between the levers.
5. In a machine of the class described a patrrix having oppositely arranged transverse recesses, and operating bolt having engaging arms adapted to embrace the recessed portion of said patrrix and mechanism whereby said bolt and patrrix are conjunctively operated consisting of a supporting bar, a hand-lever, a bolt-lever engaging the bolt, a pivot-pin common to both of the levers whereby the latter are pivoted to the bar, and pin and slot connection between the levers.
6. In a machine of the class described an operating bolt having a transverse slot, a bolt-lever extended through said slot and means whereby said bolt-lever is oscillated to reciprocate said bolt consisting of a supporting bar, a hand-lever, a pivot pin common to both of the levers whereby they are pivoted to the bar, and a pin and slot connection between the levers.
7. In a machine of the class described, the combination of a table having a ring formed with an aperture, a bolt operated through the aperture and mechanism comprising the mating feed-wheels located respectively above and beneath the table, a ratchet located on the upper feed-wheel and a trigger pivoted to the ring and having an apiced upper end formed with an inclined forward face normally in the vertical plane of the bolt, a pawl pivoted to the trigger and engaging the ratchet, and a spring for returning the trigger to normal position, substantially as described.
8. In a machine of the class described, the feeding mechanism comprising mating feed-wheels located respectively above and beneath the table, a ratchet located on the upper feed-wheel, an upwardly extending trigger having the inclined face at the top thereof, and a pawl pivoted to the trigger and overhanging and engaging the ratchet, an operating bolt adapted to engage the inclined face of the trigger and to oscillate the latter, a bolt-lever, and a hand-lever connected with the bolt-lever; substantially as described.
9. In a machine of the class described, the feeding mechanism comprising mating feed-wheels located respectively above and beneath the table, a ratchet located on the upper feed-wheel, an upwardly extending trigger having an inclined face at the top thereof, a pawl pivoted to the trigger and overhanging and engaging the ratchet, a clip on which the upper feed-wheel is mounted, a spring holding down the clip, and an adjustable trailer supporting the rear end of the clip, an operating bolt adapted to engage the inclined face of the trigger and to oscillate the latter, and mechanism whereby the bolt is reciprocated.
10. In a machine of the class described, the combination of a support, a patrrix, a bolt-lever, an operating bolt having a slot of greater depth than the width of the arm of the bolt-lever passing therethrough, a feeding mechanism, a bolt operating the feeding mechanism, and connected with the bolt of the feeding mechanism, so as to depress it in advance of the slotted bolt, a hand-lever having a pivot in common with the bolt-lever, and means for connecting the levers; substantially as described.

In testimony whereof we hereunto have set our hands at St. Louis, Missouri.
